MERRY-GO-ROUND

Henry J. Niebuhr, Lewiston, Idaho

Application August 7, 1936, Serial No. 94,850

1 Claim. (Cl. 272—48)

My invention relates generally to a merry-go-round suitable for use and operation by children, and particularly to a merry-go-round of this character designed for easy operation by one of the child passengers thereon, and an important object of the invention is to provide a simple, efficient, and attractive arrangement of this character.

Another important object of my invention is to provide an easily constructed and inexpensive merry-go-round of the character indicated above which may be readily formed of a variety of different materials, but which is preferably made up of wood, iron, steel, and bearing material such as babbitt.

Other important objects of my invention will be apparent from a reading of the following description taken in connection with the drawings, wherein for purposes of illustration I have shown a preferred embodiment of my invention.

In the drawings:—

Figure 1 is a general perspective view showing an embodiment of my invention.

Figure 2 is an enlarged bottom plan view of Figure 1.

Figure 3 is an enlarged top plan view of Figure 1 with a portion broken away.

Figure 4 is a general transverse vertical sectional view taken through Figure 3.

Referring in detail to the drawings, the numeral 5 generally designates a preferably hexagonal base which can be suitably made up of six flat pieces of timber each of which is generally designated 6 with the ends thereof beveled where they meet, and with vertically and inwardly inclined members 7 having their outer and lower ends beveled and resting on the junctions, and with bolts 8 passing through the members 7 and through the junctions and through bottom bracing and assembling plates 9 in which the heads of the bolts are countersunk as indicated by the numeral 10. Additional bolts 11 pass through the adjacent ends of the members 6, whereby the adjacent members 6 are securely fastened together and the members 7 securely fastened to the junction thereof. Interposed between the lower ends of the members 7 and the tops of the members 6 are flat iron or other suitable material radial braces 12 which intersect at the center of the base 5 and are fastened together as generally indicated by the numeral 13 in Figure 4. By means of the arrangements stated the assembling plates 9 are arranged to rest on the ground and to act as supports and also as wear plates, besides acting as braces and assembling devices.

The upper and inner ends of the inclined members 7 are set into receiving openings 15 in the block 14 which has therein a vertical bore 16 in which the vertical non-rotatable shaft 17 is supported and keyed by means of a key 18, with the lower end of the shaft 17 resting on the intersection of the radial braces 12. Upper edge portions 19 of the members 7 are cut away as indicated for clearance purposes.

The revoluble platform which is generally designated 20 and which is revolvably supported on the base 5, comprises the wooden or other suitable material annulus 21 which is open as indicated by the numeral 22 at its center and has bolted to the underside thereof radially disposed 15 and circumferentially spaced cleats 23.

A sheet metal annular plate 24 overlies the top of the annulus 21 and has a depending apron 25 depending from the outer edge thereof and along the radially outward ends of the cleats 23.

Resting on the protective sheet 24 are the pedestals 26 which support the bucket-type seats 27. A long vertical bolt 28 traverses the seat portion 29 of the seat 27 and also the pedestal 26 as well as the protective sheet 24, the annulus 21 25 and the corresponding cleat 23, whereby these parts are adequately assembled.

Rising from the radially inward edge of the protective sheet 24 is the cylindrical housing 30 which rises to a height slightly above the top of the seats and has thereon a removable cover 31 which has a flange 32 fitting around the outside of the cylinder and the top rests directly on radially inwardly projecting support brackets 33 which are circumferentially distributed around the inner part of the top of the housing as clearly shown in Figure 4. Removal of the cover 31 makes accessible the interior operating mechanism protected by the housing 30. A support 34 on the bottom of the removable top 31 contains a nut 40 35 in which is threaded a stub shaft 36 which bears on the top of the shaft 17 and holds the same down in place.

At one side of the exterior of the housing 30 is a vertical standard 37 which is fastened as 45 indicated by the numeral 38 to the top of the platform 20 and which has at its upper end a bearing sleeve 39 in which turns the crankshaft 40 which is tubular in form and has at its outer end a crank handle 41 disposed in front of one of the 50 seats 27 for operation by the passenger seated therein. The crankshaft 40 is slidable inwardly through the sleeve 39 and upon the operating shaft portion 42 between the radially outward end of which and the end of the crankshaft 40 is an 55

expanding spring 43 which normally keeps the handle 41 in a radially outwardly projected disengaged position.

On the radially inward end of the tubular shaft 40 and within the housing 30 is the clutch head 44 which is arranged to have its notches 45 operatively engage the pins 46 on the operating shaft 42, upon inward pushing of the shaft 40, whereby the shaft 40 is operatively connected 10 with the shaft 42 for rotating the beveled pinion 47 which is meshed with the beveled gear 48 which is fixed on the shaft 17. The shaft 17 and the beveled gear 48 being non-rotatable, the effect of rotating the pinion 47 in the manner indicated 15 is to cause the platform 20 to rotate about the shaft 17.

Supporting the shaft 42 within the housing 30 are the babbitt or other suitable material bearings 49 and 50, and these bearings are respectively 20 fastened on the top of rings 51 and 52 which are supported in the upper part of the housing 30 by inverted U-shaped brackets 53 distributed circumferentially around the housing and resting on similarly distributed radially outwardly 25 declining braces 54 which have their outer and lower ends passing through openings in the flooring 20 and in the annulus 21 to be held in place by a nut 55 on a J-shaped bolt 56 which has its crook projecting below the cleat 23 through which 30 it passes and engages around a rod 57 which extends between adjacent cleats and braces the same as well as anchoring the frame-work which is composed by the members 54.

The members 54 have a perpendicular portion 35 58 and from the lower end of this perpendicular portion a short radially outwardly declining portion 59 which is bolted as indicated by the numeral 60 to the radially inward ends of the cleats 23 where they project beyond the opening 40 22 in the platform annulus 21. Broken rings 61

are clamped on the upper part of the perpendicular members 58 and hold in place a bearing or support 62 in which the upper part of the shaft 17 is mounted, while a similar support 63 is disposed between the members 58 at their lower ends and held in place by bolts 64 passing through the members 58 into the bearing 63. It is to be noted that the lower ends of the vertical members 58 rest upon the top of the block 14.

Although I have shown and described herein a 10 preferred embodiment of my invention, it is to be definitely understood that I do not desire to limit the application of the invention thereto, and any change or changes may be made in the materials, and in the structure and arrangement of 15 the parts, within the spirit of the invention and the scope of the subjoined claim.

What is claimed is:—

A merry-go-round of the class described comprising a base, an upstanding shaft fixedly secured centrally of said base, a platform rotatably mounted on said shaft, a bevelled gear fixedly secured to the upper portion of said upstanding shaft, an upstanding support on said platform, a horizontally disposed rotatably mounted shaft 25 on said platform having a pinion gear on one end thereof in mesh with the bevelled gear, a hollow tubular member rotatably and slidably mounted in said upstanding support having the free end of said horizontally disposed shaft extending therein, clutch means on the inner end of said tubular member and on said horizontally disposed shaft cooperable for rotating said horizontally disposed shaft, a handle on the outer end of said tubular member, and resilient means 30 disposed within said tubular member abutting the free end of said horizontally disposed shaft for normally maintaining said clutch elements out of engagement.

HENRY J. NIEBUHR. 40
